United States Patent

Des. 234,835
Patented Apr. 8, 1975

234,835

INVERTIBLE SIGN

Elmer E. S. Lengyel, 4655 Wild Indigo 231,
Houston, Tex. 77032

Filed Sept. 7, 1973, Ser. No. 372,192

Term of patent 14 years

Int. Cl. D20—03

U.S. Cl. D96—12 E

The figure is a front view of an invertible sign showing my new design. The sign is shaded to indicate contrast. The sign is of no substantial thickness and the undisclosed side is flat and plain.

I claim:

The ornamental design for an invertible sign, substantially as shown and described.
